JEWELRY CLASP OR THE LIKE

Henry Pommier, New York, N. Y.

Application August 22, 1946, Serial No. 692,230

12 Claims. (Cl. 24—208)

1

This invention relates to clasps and more particularly to a novel, telescopically engageable clasp for jewelry, such as bracelets, chains and the like.

It is among the objects of this invention to provide a novel telescopically engageable clasp comprising a male member, a female member engageable therewith, and an element on the male member movable into embracing engagement with the female member; to provide such a clasp including abutment means on the female member engaged by the element secured to the male member, when in embracing position, to prevent longitudinal displacement of the male and female members; to provide a novel clasp including a female member having a slot therein and telescopically engageable with the male member and an element hinged to the male member and projecting through said slot for pivotal movement into embracing engagement with the female member; and in general to provide a novel easily operated and secure clasp for jewelry and the like.

These, and other objects, advantages and novel features of the invention, will be apparent from the following description and the accompanying drawing.

In the drawing:

Fig. 1 is a perspective view of a chain provided with the novel clasp of the present invention.

Fig. 2 is a plan view of the male member of the clasp in the open position.

Fig. 3 is a plan view of the female member of the clasp.

Fig. 4 is a plan view of the clasp in the closed position.

Fig. 5 is a cross-sectional view of the clasp, taken on the line 5—5 of Fig. 4.

Figs. 6 and 7 are perspective views of the female and male members, respectively, of a modified form of clasp according to the present invention.

Figs. 8 and 9 are perspective views of the female and male members, respectively, of another modified form of the invention clasp.

According to the present invention, a novel clasp is provided including longitudinally telescoping male and female members each adapted to be secured to one end of a jewelry element, such as a chain or the like. The female member is generally tubular and is provided with a longitudinal slit or slot. The male member is substantially solid and has hinge pintles aligned with the slot in the female member. A cover element is hingedly connected to the pintles of the

male member and, when the clasp members are telescoped, is movable into embracing engagement with the female member. The latter is provided with abutment means engaged by the cover element in the closed position to prevent longitudinal displacement of the clasp members.

The clasp members may have any desired cross-section, such as oval, circular, triangular or the like. The inner or male member is substantially solid in cross-section, whereas the outer, or female member, is substantially tubular. The portion of the female member embraced by the hinged cover on the male member may have its wall thickness reduced by the thickness of the cover element so that, in the closed position of the clasp, a substantially uniform exterior surface is provided.

Preferably, the abutment means comprises a lug formed integrally with the outer end of the female member, and the cover element desirably has a notch cooperable with such lug. Additionally, the radius of curvature, or the distance between the lip and hinge, of the cover element may be made less than the corresponding dimension of the female member so that a snap action is provided between the cover element and the female member. For this purpose, the cover element preferably has a length greater than half the peripheral length of the female member.

When the members are telescoped, with the cover element snapped into embracing engagement with the female member and into cooperative relation with the abutment thereon, the clasp is fixed against longitudinal separation.

The cross-sections of the clasp members may be made to conform with the cross-sectional shape of the jewelry item to which the clasp is applied. Thereby, a pleasing conforming appearance is imparted to the resultant assembly. Furthermore, the possibility of accidental opening of the clasp is avoided due to the fact that the clasp elements do not project substantially beyond the remainder of the jewelry article. Of course, a slight lip, projection or depression may be formed on the cover element to be engaged by the wearer's fingernail for readily opening the clasp and closing the same.

Referring more particularly to the drawings, Fig. 1 illustrates the clasp as applied to a jewelry item such as a "snake chain" 10. Clasp 15 comprises a substantially tubular female member 20, a substantially solid male member 25 and a cover element 30 hingedly connected to male member 25 as at 26. Hinge 26 is engageable in a longi-

tudinal slot 27 in female member 20. Female member 20 is also formed integrally, on its outer end, with a projecting lug 28 adapted to engage in a notch 31 in cover element 30 when the latter is moved into embracing engagement with female member 20.

Fig. 2 is a plan view of male member 25 and cover element 30 in the open position. As shown, in Figs. 1 and 2, male member 25 is generally oval in cross-section and is provided with hinge pintles 32 receiving between them hinge pinte 33 on cover element 30. Cover element 30 is semi-tubular in form and is preferably formed with a releasing lip or projection 34. Alternatively, a releasing notch may be formed in element 30.

Referring to Figs. 1 and 3, female member 20 is generally tubular in form, having the cross-section of an open oval, and is provided with slot 27 which receives the hinge pintles of male member 25 and cover element 30.

Figs. 4 and 5 show latch 15 in the closed position. In such position, female member 20 is longitudinally telescoped over male member 25, with hinge 26 sliding through slot 27. When the latch members are completely telescoped, cover element 30 is pivoted transversely into embracing engagement with female member 20, with lug 28 being received in notch 31 of cover element 30. The distance between hinge 26 and lip 34 of cover element 30 is less than the major cross-sectional diameter of female member 20, and cover element 30 is made slightly springy. Additionally, the peripheral length of cover element 30 is slightly greater than half the peripheral length of female element 20. Thereby, cover element 30 has a snap engagement with female member 20.

In the closed position, with the lug 28 on the outer end of female member 20 engaged in the notch 31 on the inner end of cover element 30, longitudinal separation of the latch is prevented. As the contour of the latch elements is substantially the same as that of the "snake chain" 16, the latch elements do not project substantially beyond the periphery of the "snake chain." Thereby, accidental opening of the latch due to catching on clothing or the like is substantially prevented. Additionally, a pleasing conforming appearance is prevented by the combination "snake chain" and latch.

Figs. 6 and 7 illustrate another embodiment which the latch may assume in practice. In Fig. 6, female element 40 is illustrated as cylindrical in cross-section with one wall section 41 being thicker than the diametrically opposite wall section 42, thus providing a shoulder 43. A slot 44 separates the other ends of the two wall sections. One end of wall section 41 is integrally formed with a radially projecting lug 46.

The male member 45 is illustrated in Fig. 7 as comprising a solid cylindrical portion 47 to which is hingedly connected, as at 48, a semi-cylindrical cover element 50. Cover element 50 is formed with a notch 51 and with a lip 52. The wall thickness of the cover element is substantially equal to the difference in thickness between wall sections 41 and 42 of female member 40.

The operation of the embodiments shown in Figs. 6 and 7 is the same as that shown in the embodiments of Figs. 1 through 5. Female member 40 is telescopically engaged with male member 45 by a longitudinal sliding movement. Hinge 48 is received in slot 44 and cover element 50 is then snapped transversely into engagement with wall section 42 of female member 40. The diameter of cover element 50 is made slightly less than 75 ration of said members.

the diameter of wall section 42 of female member 40, and the cover element is preferably springy and has a circumferential length slightly greater than half the circumferential length of female member 40. Thereby, cover element 50 has a snap fit on female member 40. The clasp or catch may be released by pressure on lip 52 of cover element 50 to release the latter from its embracing engagement with the female member.

Figs. 8 and 9 illustrate a further modified form of the invention. Female member 60 shown in Fig. 8 is generally substantially tubular in form and has a substantially triangular passage 61 and a slot 62. A groove 63 is formed in the outer surface of member 60 substantially opposite slot 62. Member 60 likewise has a projecting lip 64 having a concave upper surface 66. A lug 67 projects upwardly from member 60.

Male member 70, shown in Fig. 9, includes a solid triangular portion 71 connected by a hinge 72 to a cover element 75. Hinge 72 engages the concave surface 66 of projection 64. Cover element 75 has a notch 76 which receives lug 67 and member 60 when the latch is closed. Element 75 likewise has a releasing lip 77 which fits in groove 73 of member 60 in the closed position of the latch.

The operation of this embodiment of the invention is the same as that of the embodiment previously described. Portion 71 is slidably engaged in passage 61 with hinge 72 engaging surface 66 of projection 64. Element 75 is then swung transversely to embrace member 60, and lip 77 snaps into curve 63. At this time, lug 67 is engaged in recess or notch 76 preventing longitudinal separation of the latch members.

The described arrangement provides a simple and effective latch for jewelry or the like, which is easily engaged or disengaged. Among other novel features of the invention, it should be noted that the normal direction of stress on the latch is axial or longitudinal, whereas the opening movement of the cover element is transverse. Therefore, stresses tending to separate the latch will not affect the closing action of the latch, as such separating stresses are at right angles to the direction of stress needed to open the latch. The latch may be made with any desired configuration preferably conforming to the cross-sectional shape to the article to which the latch is applied.

While specific embodiments of the invention have been shown and described in detail to illustrate the application of the principles thereof, it will be understood that the invention may be otherwise embodied without departing from such principles.

What is claimed is:

1. A clasp comprising, in combination, a pair of longitudinally telescoping members; abutment means on one of said members; and an element hingedly connected to the other member on a longitudinal axis and movable transversely into embracing engagement with said one member, when said members are telescoped, to cooperate with said abutment means to prevent separation of said members.

2. A clasp comprising, in combination, a pair of longitudinally telescoping members; abutment means on the outer member; and an element hingedly connected to the inner member on a longitudinal axis and movable transversely into embracing engagement with said outer member, when said members are telescoped, to cooperate with said abutment means to prevent separation of said members.

3. A clasp comprising, in combination, a pair of telescoping members; abutment means on one of said members; and an element hingedly connected to the other member and movable into embracing engagement with said one member, when said members are telescoped, to cooperate with said abutment means to prevent separation of said members; said one member having a slot receiving the hinge connection between said other member and said element.

4. A clasp comprising, in combination, a pair of telescoping members; abutment means on the outer member; and an element hingedly connected to the inner member and movable into embracing engagement with said outer member, when said members are telescoped, to cooperate with said abutment means to prevent separation of said members; said outer member having a slot receiving the hinge connection between said inner member and said element.

5. A clasp comprising, in combination, a pair of longitudinally telescoping members; abutment means on the outer member; and an element hingedly connected to the inner member and movable transversely into embracing engagement with said outer member, when said members are telescoped, to cooperate with said abutment means to prevent separation of said members; said outer member having a longitudinal slot receiving the hinge connections between said inner member and said element.

6. A clasp comprising, in combination, a pair of telescoping members; an abutment on one of said members; and an element hingedly connected to the other member and movable into embracing engagement with said one member when said members are telescoped, said element having a notch on its free edge engageable with said abutment to prevent separation of said members.

7. A clasp comprising, in combination, a pair of longitudinally telescoping members; an abutment on one of said members; and an element hingedly connected to the other member on a longitudinal axis and movable transversely into embracing engagement with said one member when said members are telescoped, said element having a notch engageable with said abutment to prevent separation of said members.

8. A clasp comprising, in combination, a pair of longitudinally telescoping members; an abutment on the outer member; and an element hingedly connected to the inner member on a longitudinal axis and movable transversely into embracing engagement with said outer member when said members are telescoped, said element having a notch engageable with said abutment to prevent separation of said members.

9. A clasp comprising, in combination, a substantially solid inner member; a tubular outer

member telescopically engageable with said inner member; abutment means on the outer member; and an element hingedly connected to the inner member on a longitudinal axis and movable transversely into embracing engagement with said outer member, when said members are telescoped, to cooperate with said abutment means to prevent separation of said members.

10. A clasp comprising, in combination, a substantially solid inner member; a tubular outer member telescopically engageable with said inner member; abutment means on the outer member; and an element hingedly connected to the inner member and movable transversely into embracing engagement with said outer member, when said members are telescoped, to cooperate with said abutment means to prevent separation of said members; said outer member having a longitudinal slot receiving the hinge connection between said inner member and said element.

11. A clasp comprising, in combination, a substantially solid inner member; a tubular outer member telescopically engageable with said inner member; an abutment on the outer member; and an element hingedly connected to the inner member on a longitudinal axis and movable transversely into embracing engagement with said outer member when said members are telescoped, said element having a notch engageable with said abutment to prevent separation of said members.

12. A clasp comprising, in combination, a substantially solid cylindrical inner member; a substantially cylindrical outer member telescopically engageable with said inner member, a major wall portion of said outer member having a thickness substantially less than the remaining wall portion thereof; an abutment on the outer member; and a substantially semi-cylindrical element hingedly connected to the inner member, and having a thickness substantially equal to the difference in thickness of said outer member wall portions; said element having a notch engageable with said abutment to prevent separation of said members; said outer member having a longitudinal slot receiving the hinge connection between said inner member and said element.
